UNITED STATES PATENT OFFICE.

GEORGE J. OESTREICHER, OF CLEVELAND, OHIO, ASSIGNOR OF ONE-HALF
TO JOSEPH KELLER, OF CLEVELAND, OHIO.

MOVABLE PLATFORM-LADDER FOR BUILDINGS.

SPECIFICATION forming part of Letters Patent No. 740,382, dated September 29, 1903.

Application filed January 24, 1903. Serial No. 140,344. (No model.)

To all whom it may concern:

Be it known that I, GEORGE J. OESTREICHER, a citizen of the United States of America, and a resident of Cleveland, county of Cuyahoga, Ohio, have invented certain new and useful Improvements in Movable Platform-Ladders for Buildings, of which the following is a specification.

My invention relates to improvements in fire-escapes or the like for buildings; and the object of my improvement is to provide facilities in front of buildings which can be useful as fire-escapes and as balcony construction by means of which the washing of windows from the outside can be readily accomplished and which may be otherwise useful in case of repairs, painting, &c. I attain this object in and with a structure constructed substantially as illustrated in the accompanying drawings, in which—

Figure 1 represents a partial view in elevation of a building and a side view of a movable platform-ladder. Fig. 2 is another view in elevation of a building and a face view of said movable platform-ladder. Fig. 3 is a plan view of the floor of one of the platforms of said ladder, and Fig. 4 is a perspective view of said platform and a part of the ladder.

Like letters of reference denote like parts of the drawings and specification.

In the main my invention consists of the iron ladder A, attached to which are a number of platforms B, which are arranged approximately at the height of the windows, the entire structure being equipped for movement along the fronts of buildings. As shown, there is provided a track or railing C at about the height of the second story, said track being supported in any suitable manner. Each of the poles or "uprights" of the ladder is provided at its lower terminal with a roller or caster b, which rolls and is guided upon the rail C, thus forming a support for the ladder. At their upper ends the uprights are provided with guide-rolls c, which prevent the ladder from tilting outwardly. The guideway d is so placed that the ladder may assume a position slightly out of "plumb" away from the building, in which instance the rolls c remain continually in action.

Along the whole length or height of the

ladder extends a shaft D, which is guided and supported in bearings, as shown at e. (See Figs. 1 and 2.) The terminals of said shaft carry spur-gears ff', which engage with the racks g g'. Furthermore, at convenient height above each platform are securely fastened the hand-wheels h h h, and by these means it is made possible to move the ladder along the front of buildings as conditions may require.

In each of the platforms there are trap-doors jj, which, however, are normally left open, so that in case of fire one may without interruption descend along the rungs of the ladder. In closing the doors jj they serve as the floor of the balcony and upon which the operator can stand in washing windows or performing other work which may become desirable.

As will be seen, the ladder portion is located at a point away from and parallel with the face of the building, the platforms or balconies being located between the ladder and the building-front. This is of especial importance when used as a fire-escape, inasmuch as its position is such as to not only be out of contact with the walls of the burning building, but also at a point where the flames passing out of the window will not readily reach the user of the escape nor be apt to destroy or highly heat the rungs of the ladder. Furthermore, the ladder being on the outer side of and forming one of the faces of the platform the latter can be readily entered from the window, and when used simply as a balcony for observation purposes or for use in operating on the windows the ladder will in no way obstruct the view of the occupant or prevent free movement of the person during the washing or other operation. The particular means for moving the ladder along the front of a building are of great advantage, inasmuch as the hand-wheels, being on a horizontal plane with a vertical axis, are readily accessible to the occupant of a balcony, the necessary movement required in operating the wheels not requiring any strained movements or position of the operator, such as would be required in cases where the ladder is moved by ropes or cables extending lengthwise of the ladder and adapted to be moved by the operator pulling

thereon in a direction longitudinally of the rope or cable.

What I claim, and desire to secure by Letters Patent, is—

5 1. The combination with a ladder movable along the front of a building and guided at its opposite ends; of a series of balconies or platforms carried by said ladder, said platforms being interposed between the ladder and the front of the building, the ladder forming one of the sides of the balcony; and means, operable from each of the balconies, for moving said ladder.

15 2. The combination with a ladder movable along the front of a building and guided at its opposite ends; of a series of balconies or platforms carried by said ladder, said platforms being interposed between the ladder and the front of the building, the ladder forming one of the sides of the balcony, each balcony having a trap-door floor; of means

operable from each of the balconies, for moving said ladder.

3. The combination of a ladder supported at its opposite ends and movable along the front of a building; a shaft extending longitudinally of the ladder, said shaft having gears located at its opposite ends; racks carried by the building and adapted to coöperate with said gears to move the ladder; balconies or platforms carried by the ladder and interposed between it and the front of the building, the ladder forming one of the sides of the balcony; and hand-wheels carried by the shaft adjacent to the several balconies, whereby the ladder may be moved along its supports by a movement of any of the hand-wheels. 25 30 35
